UNITED STATES PATENT OFFICE.

WILLIAM J. LUTTON, OF PATERSON, NEW JERSEY, ASSIGNOR OF ONE-HALF TO
MAURICE FRANCK, OF PATERSON, NEW JERSEY.

WINDING MACHINE.

Application filed December 18, 1923. Serial No. 681,378.

To all whom it may concern:

Be it known that I, WILLIAM J. LUTTON, a citizen of the United States, and resident of Paterson, in the county of Passaic and 5 State of New Jersey, have invented a new and useful Improvement in Winding Machines, of which the following is a specification.

This invention relates to bobbin winding 10 machines, and has for its object to provide a device for automatically moving the filled bobbin out of contact with its driving element.

A further object is to provide a device 15 which is controlled and operated by the material wound upon the bobbin.

Another object is to provide a gravity operated device for automatically stopping the rotation of the bobbin.

20 Another object is to provide a device having means operated by the material wound on the bobbin for imparting a quick or sudden movement to the device at the moment the bobbin is filled to the desired amount, 25 whereby the bobbin will be lifted from its driving element and the winding and rotation stopped.

Another object is to provide certain improvements in the form, construction and arrangement of the several parts whereby 30 the above named and other objects may be effectively attained.

A practical embodiment of my invention is represented in the accompanying drawing, 35 in which—

Fig. 1 represents a plan view of a portion of a bobbin winding machine having my improved device applied thereto.

Fig. 2 represents a front elevation of the 40 same.

Fig. 3 represents a vertical section taken in the plane of the line III—III of Fig. 2, looking in the direction of the arrows.

Fig. 4 represents a detail front elevation of the same with the bobbin removed and one of its supports in section.

Fig. 5 represents a vertical section taken through the bobbin in close proximity to the means for lifting the bobbin from its driving element, the bobbin being fully wound with material and the device in the position it will assume prior to the bobbin being lifted from its driving element, and

Fig. 6 represents a similar view of the parts in another position.

The winding machine to which my improved device is applied is of well known and approved construction and I have shown only so much of a winding machine as will give a clear understanding of my invention as applied thereto.

The cross rods of the machine are denoted by 1, 2, the brackets by 3, 4 secured to the rods, which brackets are provided with recesses 5, 6 for the reception of the ends of the pintles 7 of the bobbin. The bobbin is provided with the usual flanges 8 and hub 9, which hub extends into position to rest upon a driving element 10, which is fast on the continuously rotating shaft 11. A 70 traverse bar 12 is mounted to slide in bearings 13 projecting from the bracket 4 and reciprocated in any well known and approved manner. The traverse bar 12 is also provided with a thread guide 14 yielding secured thereto by oppositely disposed spring actuated fingers 15 carried by the bearings.

Clamping plates 16, 17 are arranged to be secured to the rods 1, 2 by a screw 18, the head of which engages the plate 16 and the threaded end is screwed into the plate 17. The plate 16 is provided with a bracket 19, which extends laterally therefrom and is arranged to form a support and journal for a 85 shaft 20.

A depending curved arm 21 is secured to one end of the shaft 20 by means of a set screw 22, the lower end of which arm is bifurcated at 23 to receive a roller 24 eccentrically mounted on a pin 25 journaled in the bifurcated end 23 of the arm. This arm is disposed so that the roller 24 will contact with the material wound on the bobbin and is normally held in position by means of a weighted member 26, which forms a counterbalance for the arm 21. The weighted member 26 is adjustably secured to the shaft 20 by means of a set screw 27.

The amount of material wound on the bobbin is controlled by the position of the arm 21 with respect to the bobbin. The position of the arm 21 is controlled and adjusted by means of a screw 28 threaded in the weighted member 26 and arranged 105 to engage the rod 1.

An upwardly extending arm 28 is also secured to the shaft 20 and has linked thereto a curved shoe 29, which is pivoted at 30 in the arm 28 and arranged to normally rest upon the driving element 10. The free end of the shoe 29 is located in position to be moved on the driving element 10 and under the hub 9 of the bobbin, thereby lifting the bobbin out of contact with its driving element and stopping its rotation.

The eccentrically mounted roller 24 carried by the arm 21 is so arranged that it will assume the position shown in dotted outline in Figs. 1 to 3 inclusive, until the 15 bobbin has been filled to the predetermined amount, whereupon the surface friction between the material on the bobbin and the roller will cause the roller to rotate and move the arm 21 so that the weighted member 26 will be brought toward a vertical position. As the roller is further rotated, it will move the arm 21 and rock the shaft 20 so that the weighted member 26 will fall by gravity past the vertical center toward 25 the bobbin, to the position shown in Figs. 5 and 6. In this position it will be seen that the curved shoe 29 was caused to enter between the hub 9 and the driving element 10, by the rocking of the shaft 20 and the 30 arm 28 thereby stopping the rotation of the bobbin.

The amount of material wound upon the bobbin may also be controlled and regulated by arcuately adjusting the arm 21 on the 35 shaft with respect to the shoe 29, and setting the weighted member 26 to counterbalance the arm 21.

It is to be understood that various changes 40 may be resorted to in the form, construction and arrangement of the several parts without departing from the spirit and scope of my invention; and hence, I do not intend to be limited to the details herein shown and described except as they may be included 45 in the claims.

What I claim is:

1. In a winding machine the combination 50 with a bobbin and its driving element, of a shaft, an arm mounted thereon in position to contact with the material wound on the bobbin and actuated thereby, and means carried by the shaft for moving the bobbin away from its driving element.

2. In a winding machine the combination 55 with a bobbin and its driving element, of a shaft, an arm mounted thereon in position to contact with the material wound on the bobbin and actuated thereby, a gravity operated member on said shaft for counterbalancing said arm, and means carried by the shaft for moving the bobbin away from its driving element.

3. In a winding machine the combination 60 with a bobbin and its driving element, of a shaft, an arm mounted thereon, a roller on

said arm in position to contact with the material wound on the bobbin for actuating said arm, and means carried by the shaft for moving the bobbin away from its driving element.

4. In a winding machine the combination 70 with a bobbin and its driving element, of a shaft, an arm mounted thereon, a roller eccentrically pivoted on said arm in position to contact with the material wound on the bobbin for actuating said arm, and means carried by the shaft for moving the bobbin away from its driving element.

5. In a winding machine the combination 80 with a bobbin and its driving element, of a shaft, an arm mounted thereon, a roller on said arm in position to contact with the material wound on the bobbin for actuating said arm, a gravity operated member on said shaft for counterbalancing the arm, 85 and means carried by the shaft for moving the bobbin away from its driving element.

6. In a winding machine the combination 90 with a bobbin and its driving element, of a shaft, an arm mounted thereon, a roller eccentrically pivoted on said arm in position to contact with the material wound on the bobbin for actuating said arm, a gravity operated member on said shaft for counterbalancing the arm, and means carried by 95 the shaft for moving the bobbin away from its driving element.

7. In a winding machine the combination 100 with a bobbin and its driving element, of a shaft, an arm mounted thereon, a roller on said arm in position to contact with the material wound on the bobbin for actuating said arm, a gravity operated member on said shaft for counterbalancing the arm, means for limiting the movement of said 105 member for controlling the amount of material to be wound on the bobbin, and means carried by the shaft for moving the bobbin away from its driving element.

8. In a winding machine the combination 110 with a bobbin and its driving element, of a shaft, an arm mounted thereon, a roller eccentrically pivoted on said arm in position to contact with the material wound on the bobbin for actuating said arm, a gravity operated member on said shaft for counterbalancing the arm, means for limiting the movement of said member for controlling the amount of material to be wound on the bobbin, and means carried by the shaft for moving the bobbin away from its driving element.

9. In a winding machine the combination 115 with a bobbin and its driving element, of a shaft, an arm mounted thereon, a roller on said arm in position to contact with the material wound on the bobbin for actuating said arm, and a shoe carried by the shaft for moving the bobbin away from its driving 120 element.

10. In a winding machine the combination with a bobbin and its driving element, of a shaft, an arm mounted thereon, a roller eccentrically pivoted on said arm in position to contact with the material wound on the bobbin for actuating said arm, and a shoe carried by the shaft for moving the bobbin away from its driving element.
11. In a winding machine the combination with a bobbin and its driving element, of a shaft, an arm mounted thereon, a roller on said arm in position to contact with the material wound on the bobbin for actuating said arm, and an oscillating shoe carried by the shaft for moving the bobbin away from its driving element.
12. In a winding machine the combination with a bobbin and its driving element, of a shaft, an arm mounted thereon, a roller eccentrically pivoted on said arm in position to contact with the material wound on the bobbin for actuating said arm, and an oscillating shoe carried by the shaft for moving the bobbin away from its driving element.
13. In a winding machine the combination with a bobbin and its driving element, of a shaft, an arm mounted thereon, a roller on said arm in position to contact with the material wound on the bobbin for actuating said arm, a gravity operated member on said shaft for counterbalancing the arm, and a shoe carried by the shaft for moving the bobbin away from its driving element.
14. In a winding machine the combination with a bobbin and its driving element, of a shaft, an arm mounted thereon, a roller eccentrically pivoted on said arm in position to contact with the material wound on the bobbin for actuating said arm, a gravity operated member on said shaft for counterbalancing the arm, and a shoe carried by the shaft for moving the bobbin away from its driving element.
15. In a winding machine the combination with a bobbin and its driving element, of a shaft, an arm mounted thereon, a roller on said arm in position to contact with the material wound on the bobbin for actuating said arm, a gravity operated member on said shaft for counterbalancing the arm, and an oscillating shoe carried by the shaft for moving the bobbin away from its driving element.

said arm in position to contact with the material wound on the bobbin for actuating said arm, a gravity operated member on said shaft for counterbalancing the arm, and an oscillating shoe carried by the shaft for moving the bobbin away from its driving element.

16. In a winding machine the combination with a bobbin and its driving element, of a shaft, an arm mounted thereon, a roller eccentrically pivoted on said arm in position to contact with the material wound on the bobbin for actuating said arm, a gravity operated member on said shaft for counterbalancing the arm, and an oscillating shoe carried by the shaft for moving the bobbin away from its driving element.

17. In a winding machine the combination with a bobbin and its driving element, of a shaft, an arm mounted thereon, a roller on said arm in position to contact with the material wound on the bobbin for actuating said arm, a gravity operated member on said shaft for counterbalancing the arm, means for limiting the movement of said member for controlling the amount of material to be wound on the bobbin, and a shoe carried by the shaft for moving the bobbin away from its driving element.

18. In a winding machine the combination with a bobbin and its driving element, of a shaft, an arm mounted thereon, a roller eccentrically pivoted on said arm in position to contact with the material wound on the bobbin for actuating said arm, a gravity operated member on said shaft for counterbalancing the arm, means for limiting the movement of said member for controlling the amount of material to be wound on the bobbin, and an oscillating shoe carried by the shaft for moving the bobbin away from its driving element.

In testimony, that I claim the foregoing as my invention, I have signed my name this 21st day of November, 1923.

WILLIAM J. LUTTON.
